UNITED STATES PATENT OFFICE.

EDWARD HUBER, OF MARION, OHIO.

GRAIN-SEPARATOR.

SPECIFICATION forming part of Letters Patent No. 320,356, dated June 16, 1885.

Application filed March 25, 1885. (No model.)

To all whom it may concern :

Be it known that I, EDWARD HUBER, a citizen of the United States, and a resident of Marion, in the county of Marion and State of Ohio, have invented certain new and useful Improvements in Grain-Separators; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a longitudinal vertical sectional view of a thrashing-machine equipped with my improvements; and Fig. 2 is a plan view of the bottom of the same, which is the subject of my improvements.

The same letters refer to the same parts in 20 both the figures.

This invention relates to thrashing-machines or grain-separators; and it has particular reference to certain improvements in the construction of the oscillating bottom and the 25 part of the same overhanging the shoe, the objects of the said improvements being to effect a more thorough separation of the grain from the chaff and straw.

The invention consists in the details of construction and arrangement which will be hereinafter fully described, and particularly pointed out in the claims.

In the drawings hereto annexed, A designates the frame of the machine, B the straw-carrier, and C the shoe, all of which are constructed in the usual manner, and in which no novelty is herein claimed.

D designates the oscillating bottom, which is mounted in suitable hangers and arranged 40 to be oscillated by any suitable mechanism. Said bottom consists of a solid or imperforate front part, E, the rear end of which overhangs or extends over the front end of the shoe. Said part E is provided with a series of longitudinal ratchet-bars, F F, increasing in 45 height from the front toward the rear end and extending slightly over the tail end G of the bottom, which is hinged to the part E, as shown, and which is likewise supported by 50 suitable hangers. The tail end or part G of the bottom consists of a board, which is pro-

vided for the greater portion of its length with inverted funnel-shaped perforations H H, its rear end only being left solid or imperforate. The upper side of the bottom board, G, is provided with longitudinal ratchet-bars I I, increasing in height toward the rear end, and terminating in arms J J, which extend over the tailings-spout K. The under side of the 55 perforated portion of the bottom board, G, is provided with one or more transverse forwardly-inclined deflectors L L, the function 60 of which is to intercept the blast and cause it to act more effectively upon the material passing over the bottom. The board G is, of course, 65 directly above the riddle M, upon which the grain falls through the openings H H.

From the foregoing description, taken in connection with the drawings hereto annexed, the operation and advantages of this invention will be readily understood. The ends of the rack-bars F will dump the grain and chaff from the bottom E onto the hinged perforated part G, where it is immediately exposed to the blast. The imperforate rear end of the bottom board, G, prevents straw and chaff from running into the riddle below, thus keeping the latter free from clogging. This imperforate part also prevents the blast from acting 70 on the heavy rubbish, and, allowing it to drop upon the ratchet-bars over the said imperforate space, it will again be agitated and moved outward until the blast will take it again at the rear end of the imperforate space and carry it over the arms or extensions J J of 75 ratchet-bars I I and out of the machine. By this construction the grain is most thoroughly 80 separated from the chaff and all waste avoided.

Having thus described my invention, I claim and desire to secure by Letters Patent of the 90 United States—

1. In a grain-separator, the oscillating bottom having hinged tail section or extension, and provided with longitudinal ratchet-bars extending slightly over said tail section, substantially as and for the purpose set forth.

2. The combination, with the imperforate oscillating bottom, of the hinged tail section, perforated throughout the greater part of its length, and having imperforate rear end, and the blast-fan, substantially as and for the purpose set forth.

3. The combination, with the tailings-spout and the oscillating bottom, of the hinged tail section having longitudinal ratchet-bars provided with rearwardly-extending arms extending over the tailings-spout of the machine, substantially as and for the purpose herein set forth.

4. The combination of the oscillating bottom, the tail section having imperforate rear end and perforated front end, and hinged to the rear end of the oscillating bottom, and the deflecting boards secured transversely under the same, substantially as and for the purposes herein set forth.

15 5. The combination of the tailings-spout, the oscillating bottom having longitudinal

ratchet-bars extending slightly beyond its rear edge, the hinged tail section having perforated front and imperforate rear end, longitudinal ratchet-bars secured on the upper side of said tail section and extending at its rear end over the tailings-spout, and transverse deflecting-boards secured on the under side of said tail section, all arranged and operating substantially as and for the purpose herein set forth. 20 25

In testimony that I claim the foregoing as my own, I have hereunto affixed my signature in presence of two witnesses.

EDWARD HUBER.
